[57] **CLAIM**

The ornamental design for a self-contained lint shaver apparatus, as shown and described.

DESCRIPTION

FIG. 1 is a front elevational view of a self-contained lint shaver apparatus showing my new design;

FIG. 2 is a rear elevational view thereof;

FIG. 3 is a bottom plan view thereof;

FIG. 4 is a top plan view thereof;

FIG. 5 is a right side elevational view thereof;

FIG. 6 is a left side elevational view thereof;

FIG. 7 is a front elevational exploded view thereof;

FIG. 8 is a left side elevational view thereof taken along lines 8—8 of FIG. 7 and looking in the direction of the arrows;

FIG. 9 is a right side elevational view thereof taken along lines 9—9 of FIG. 7 and looking in the direction of the arrows;

FIG. 10 is a right side elevational view thereof taken along lines 10—10 of FIG. 7 and looking in the direction of the arrows;

FIG. 11 is a left side elevational view thereof taken along lines 11—11 of FIG. 7 and looking in the direction of the arrows.
